UNITED STATES PATENT OFFICE.

JOSEPH C. SOEMER, OF NEWARK, NEW JERSEY.

DESK-BASKET PAPER HOLDER AND CLIP.

1,328,971.

Specification of Letters Patent. Patented Jan. 27, 1920.

Application filed November 16, 1918. Serial No. 262,864.

To all whom it may concern:

Be it known that I, JOSEPH C. SOEMER, citizen of the United States, residing at Newark, in the county of Essex and State 5 of New Jersey, have invented certain new and useful Improvements in Desk-Basket Paper Holders and Clips, of which the following is a specification.

This invention relates to desk basket paper holders and clips and belongs directly with that class or type of desk baskets that are provided with means for removably holding the sheets of paper in the basket against accidental displacement when the 10 basket is quickly moved, or inadvertently overturned, or situated in the path of the air stream from an electric fan or open window. This invention is believed to be an improvement upon the desk basket invented by me 15 and set forth in my application for Letters Patent of the United States, filed October 7, 1918, Serial No. 257,221.

The object of this invention is the production of a desk basket having a paper holder frame pivoted to the basket frame by which sheets of paper may be held in the basket, the free end of the paper holder frame bearing a paper clip, which is intended to additionally secure the sheets of 20 paper in the basket, or to hold a part of the number of sheets clamped against the holder frame and thereby kept separated from the other sheets in the basket when such separation is desired. It is also an object of this 25 invention to produce a desk basket having a pivoted paper holder frame that may be brought to rest in a raised position, into which it may be upwardly turned and wherein it is movably maintained usually by 30 the force of a light spring. In its raised position the paper holder frame co-operating with the paper clip devices borne by the free end of the frame, constitute a very convenient copyholder for the use of typists or 35 other copyists.

Another object of this invention is the production of a desk basket of the nature set forth whereof the parts have special construction and particular arrangement one 40 with regard to another. The accompanying drawings illustrate the preferred formation and disposition of the parts of this invention, and Figure 1 represents a top plan view of all the parts assembled. Fig. 2 is 45 a cross-section of the basket upon the broken line 2-2 of Fig. 1, showing the paper holder

frame in its raised position. Fig. 3 is a side view, full size, of the paper clip members in section upon the broken line 3-3 of Fig. 1.

Throughout the description and drawings, the same letter is employed to refer to the same part.

Considering the drawings, the basket comprises the frame A and the longitudinal 65 wires B and cross wires b. One end of the basket frame A has a drop or downwardly-extended portion C, which will be again mentioned.

The part termed for the purposes of this 70 description the paper holder frame, comprises the longitudinal leg D having the pivotal connection d with the end of the basket frame. The holder frame is usually made in practice of a single piece of formed wire, 75 and at the free end of the holder frame the wire is bent from the leg D into the transverse portion E, and then into an outward extension e, which forms one finger piece of 80 the paper clip on the free end of the holder frame, and will be further mentioned. From the extension e the wire extends toward the drop C in the frame A, and before reaching the drop the wire is transversely and diagonally extended in the part marked 85 f, and thence in a straight portion G parallel with the part F. The wire is then turned about the basket frame on one side of the drop C, making the pivotal joint g, and extends thence transversely in a bridge piece 90 or stop H. The wire is then again bent and turned about the basket frame A on the other side of the drop C, forming the pivotal joint h on the remaining side of the drop as illustrated. Thus, the wire of 95 the middle portion of the holder frame is pivotally attached to the basket frame on both sides of the drop or downward extension C. From the connection h the wire continues in a short, straight portion j parallel with the like portion G, and then diagonally across in the part marked 100 j. The two diagonal parts f and j cross each other as shown, and their junction is in practice usually soldered. From the diagonal part j, the wire is continued in the straight portion K, parallel with and of like structure to the part F, and projects in a second extension k that is a duplicate of the extension e, against which it is arranged, 105 as best set out in Fig. 3, and to which it is usually soldered in practice. These two ex-

tensions *e* and *h* form one finger piece, the relatively stationary piece of the paper clip. From the extension *h* the wire extends in a transverse portion *L*, and turns into a second leg at the side, the side being marked *M* and having a pivotal joint at the end referred to by the letter *m*. The portions of wire just described complete the paper holder frame, and, it may be here stated that 10 the parts *F*, *K*, and others extending lengthwise of the middle of the holder frame add stiffness thereto.

To the free end of the paper holder frame is a wire paper clip member comprising 15 the clamping or jaw portion *N*, which, coöperating with the middle or stiffening portion described acts to clamp sheets of paper against the paper holding frame. The clip member has pivotal joints *n* and *O* located at the sides of the extension of the paper holder frame formed by the portions 20 designated by the letters *e* and *h*. As best set out in Fig. 3, the wire of the clip member is formed into a yoke or extension *P* 25 similar to the extensions *e* and *h*. The yoke *P* connects the two pivotal joints or bearings *n* and *O* of the clip member with the free end of the holder frame. The yoke *P* is the movable finger piece of the paper clip devices, and a coil spring *Q* has the part *R* attached to the composite extension *e*, *h*, and the two bends *S*, *s* attached to the yoke *P* as shown in Figs. 1 and 2.

In the operation of this invention, the 35 free end of the paper holder frame, which is constructed to enter the basket, serves to hold any sheets of paper placed therein. From its position within the basket the free 40 end of the holder frame may be swung upwardly into the raised position set out in Fig. 2, and in this position a sheet of paper may be held in the position indicated by the broken line rectangle in Fig. 2, thus serving 45 as a copyholder for a typist. The operation of the paper clip devices borne by the free end of the paper holder frame is thought to be apparent from the drawings and the foregoing explanation.

Having now described this invention and 50 the mode of its operation, what I claim is:—

1. In a desk basket, the combination with a basket frame, of a paper holder frame pivotally attached to the basket frame and having a free end constructed to enter the basket, and a paper clip member pivotally secured to the said free end of the paper holder, the said paper holder having a portion constructed to form the complementary member of the paper clip.

- 60 2. In a desk basket, the combination with a basket frame, of a paper holder frame

pivotaly attached to the basket frame and having a free end constructed to enter the basket, means for removably sustaining the said holder in a raised position, and a paper 65 clip member pivotally secured to the said free end of the paper holder, the said paper holder having a portion constructed to form the complementary member of the paper clip.

3. In a desk basket, the combination with a basket frame, of a paper holder frame pivotally attached to the basket frame and having a free end constructed to enter the basket, and a paper clip borne by the said 70 free end of the paper holder frame.

4. In a desk basket, the combination with a basket frame, of a paper holder frame pivotally secured to the said basket frame and having one free end constructed to enter the 80 basket, the said paper holder frame having a middle stiffening portion extending lengthwise of the said paper holder frame, and a paper clip member pivotally attached to the said free end of the holder frame and 85 arranged to act against the said stiffening portion of the holder frame to clamp sheets of paper against the said holder frame.

5. In a desk basket, the combination with a basket frame, of a paper holder frame pivotally secured to the said basket frame and having one end free and constructed to enter the basket, the said free end of the holder frame having an outward extension, a paper 90 clip member pivotally secured to the said 95 free end of the holder frame on both sides of the said extension, the said holder frame extension forming one of the finger pieces of a paper clip, and the said holder frame having a portion constructed and arranged to 100 coöperate with the said clip member to clamp sheets of paper against the said holder frame.

6. In a desk basket, the combination with a basket frame, of a paper holder frame 105 comprising side legs and a middle stiffening portion pivotally attached to the said basket frame, the said holder frame having a free end constructed to enter the basket and provided with an outward extension forming 110 one of the finger pieces of the paper clip, a paper clip member pivotally secured to the said free end of the holder frame on both sides of the said extension, and the said 115 clip member and said middle stiffening portion of the holder frame being arranged to coöperate to form a paper clip for clamping sheets of paper against the said holder frame.

In testimony whereof I affix my signature.

JOSEPH C. SOEMER.
